Mr. Mallory
Charles

United States Patent Office.

EDWARD F. STEPHENS, OF TOWANDA, PENNSYLVANIA.

Letters Patent No. 65,181, dated May 28, 1867.

CARD OR LABEL-HOLDER.

The Schedule referred to in these Letters Patent and making part of the same.

TO ALL WHOM IT MAY CONCERN:

Be it known that I, **EDWARD FELIX STEPHENS**, of the borough of Towanda, in the county of Bradford, and State of Pennsylvania, have invented a new and improved Card or Label-Holder to facilitate the attaching, removing, and changing cards or labels from drawers, boxes, and so forth; and I do hereby declare that the following is a full and exact description thereof, reference being had to the accompanying drawings, and to the letters of reference marked thereon, making a part of this specification.

The nature of my invention consists in a metallic plate so formed that by turning points at its corners, at right angles to the plate, the holder may be securely attached to the drawer, box, or so forth, and three sides of the plate turned over upon its face, to hold the card or label, and to enable the changing of the same without detaching the plate.

To enable others skilled in the art to make and use my invention, I will proceed to describe its construction and operation.

I make the plate, which is formed into the holder, of any malleable metallic substance or alloy of the same, of any size required for the card or label to be used. The shape of the plate before the points and flanges are bent is represented by—

No. 1 of the accompanying drawing.

No. 2 represents the elevation of the label-holder as fixed in place with label partly inserted.

No. 3 represents the longitudinal section.

No. 4 a cross-section.

To form the holder from a plate as represented in fig. No. 1, bend the points marked C D E and F backward at right angles to the plate, which is designed to secure the plate to the drawer, box, or so forth, to be labelled; bend the borders G, H, and I forward upon the face of the plate, so that the margins J, K, and L will remain at M, N, and O, leaving a sufficient space between the flanges so turned and the body of the plate as to allow of an easy insertion or withdrawal of the card or label.

What I claim as my invention, and desire to secure by Letters Patent, is—

The form of the plate as cut out of one piece of metal, the points marked C, D, E, and F, which secure the holder to the drawer or so forth, without the use of nails or other means of fastening, and the flanges G, H, and I, so turned as to hold the card or label; and permit the same to be changed without detaching the holder.

EDWARD FELIX STEPHENS.
